UNITED STATES PATENT OFFICE.

HOWARD E. WATKINS, OF NEW YORK, N. Y., ASSIGNOR TO THE OXLEY & ENOS MANUFACTURING COMPANY, OF SAME PLACE.

DESIGN FOR A GAS OR ELECTRIC LIGHT FIXTURE.

SPECIFICATION forming part of Design No. 25,808, dated July 21, 1896.

Application filed April 13, 1896. Serial No. 587,432. Term of patent 7 years.

To all whom it may concern:

Be it known that I, HOWARD E. WATKINS, a citizen of the United States, residing at New York city, in the county and State of New York, have invented and produced a new and original Design for Gas and Electric Light Fixtures; and I do hereby declare the following to be a full, clear, and exact description of the same, reference being had to the accompanying drawings, forming a part thereof, in which—

Figure 1 represents an elevation of a chandelier embodying my design, and Fig. 2 a cross-section taken on either of the lines 2 2 15 of Fig. 1.

The leading features of my design relate to the "canopy" and to the "body-shell" technically so called, said canopy and said body-shell having thereon a series of concave depressions with alternating flat or slightly curved facets.

Referring to Fig. 1, A is the main stem of a pendent fixture ordinarily known as a "chandelier." This stem is not shown in its full length, as is indicated by the part broken away. B is the canopy. D is the body-shell of the fixture. E is one of the arms of the fixture, which, however, is not a part of the design.

The body-shell D comprises the central 30 part or zone F, the upper part G, of a generally conical shape, and the lower part H, of a generally conical shape, but longer than the part G.

The parts F, G, and H are formed with a 35 series of concave depressions I, with alternating flat or slightly curved facets J, as shown in Fig. 2. The canopy B is also provided with a series of concave depressions, and with alternating flat or slightly curved facets. 40

K is the representation of a conventional scroll or ornamentation formed in or on one of the concave depressions, but which is not a part of the design.

The canopy and body-shell are generally 45 assembled in the relation indicated in the drawings.

What I claim is—

The design for a gas or electric light fixture, substantially as shown and described. 50

This specification signed and witnessed this 25th day of February, 1896.

HOWARD E. WATKINS.
